United States Patent Office

Des. 211,399
Patented June 11, 1968

211,399

COMBINATION KEY CHAIN AND FIRE LIGHTER

Richard C. Martin, Boulder, Colo., assignor to Ute Mountain Supply Company, Denver, Colo., a corporation of Colorado

Filed July 3, 1967, Ser. No. 7,708

Term of patent 14 years

(Cl. D50—4)

FIG. 1

FIG. 3

FIGURE 1 is a top plan view showing my combination key chain and fire lighter, with said sleeve in retracted position;

I claim:

The ornamental design for a combination key chain and fire lighter, as shown and described.
